UNITED STATES PATENT OFFICE.

CLARK A. SIGAFOOS, OF OMAHA, NEBRASKA.

STACKER FOR FOLDING-MACHINES.

1,238,207.

Specification of Letters Patent. Patented Aug. 28, 1917.

Application filed April 19, 1915. Serial No. 22,481.

To all whom it may concern:

Be it known that I, CLARK A. SIGAFOOS, a citizen of the United States, and a resident of Omaha, in the county of Douglas and State of Nebraska, have invented certain new and useful Improvements in Stackers for Folding-Machines, of which the following is a specification.

My invention relates to stackers for paper folding machines, and it is the object thereof to provide, in connection with such a machine, a packing and receiving device for folded sheets, adapted to receive all sizes of articles within the capacity of the folding mechanism without requiring adjustment for the different sizes. The packer is particularly adapted for use in connection with a simple portable machine for folding pamphlets, circulars and like articles, where- 10 in the sheets to be folded are of moderate size and require the making of only a single fold by the machine at each operation thereon; and for convenience of description the packer is shown as constructed and operating 15 in connection with such a folding mechanism.

In the accompanying drawings Figure 1 is a side view of a machine embodying my invention, adjacent parts of the frame being 20 broken away to show clearly the more remote operating parts, Fig. 2 is a partly diagrammatic side view showing the operation of the packing and receiving mechanism, Fig. 3 is a partial plan view of the machine, 25 the feed-table and parts of the frame being broken away at one side to show the underlying mechanism, and Fig. 4 is a detail perspective view of the sliding frame of the receiver for the folded sheets.

40 In carrying out my invention I provide a suitable frame which, in the structure shown, comprises an upper rectangular horizontal portion 1, an intermediate rectangular horizontal portion 2 and vertical legs 3. The lower ends of the legs 3 are provided with caster-wheels 4, to facilitate the moving of the machine from place to place. At the rearward side of the machine, below the frame-portion 2, is a transverse shaft 75 45 with which one end of a plate 5 is slidably and pivotally connected. On the lower side of said plate is secured a small electric motor 6 of which the shaft carries a grooved step-pulley 7. From said pulley a round belt 8 extends to a pulley 9 carried on one 50 end of a transverse shaft 10 journaled in the

upper part of the frame, as shown. The motor and plate 5 are freely swingable about the axis of the shaft 75, so that the weight thereof causes a constant tension on the belt 60 8 and permits the changing of the belt to the different steps of the pulley 7 without altering the length of the belt. Movement of the plate 5 laterally along the shaft 75 permits the different steps of the pulley 7 65 to be brought into proper alinement with the pulley 9. A simple and convenient variable-speed drive is thus provided for the shaft 10. To prevent excessive downward swinging of the plate 5, should the belt 8 be 70 removed or broken, a chain 85 is provided, the same being normally slack and connecting the front end of the plate with the frame, as shown.

On the shaft 10 between the sides of the 75 frame is carried a knurled roller 11 which is adapted to coöperate with a similar roller 12 disposed parallel thereto and suitably journaled in the frame, the two rollers being operatively connected by a pair of gears 80 13 and 14 arranged at one end thereof, as shown in Fig. 3.

On the end of the shaft 10 opposite the pulley 9 is carried a small pulley 15 from which a belt 16 extends to a pulley 17 carried on a stub-shaft 18. On said shaft is a small gear or pinion 19 which meshes with a gear 20 carried on the end of the cam-shaft 21, said shaft being journaled in suitable bearings near the rearward side of the machine 90 between the frame-portions 1 and 2. By the described driving connections the cam-shaft is driven at a low speed relatively to that of the folding-rollers 11 and 12.

An inclined feed-table 22 is arranged at 95 the front side of the machine, the lower edge of the table being adjacent to the upper side of the roller 12. Behind the roller 11 is an inclined slotted plate or gage-table 23 of which the upper surface is in the same plane 100 as the surface of the table 22, being practically a continuation of said table behind the rollers. The plate 23 is supported by transverse bars 24 and 25, of which the ends are secured to the sides of the frame, the plate 105 passing over the bar 24 and beneath the bar 25. To the bar 25 are secured the lower ends of a plurality of guide-rods 26 which extend parallel with the plate 23 to points near the upper edge thereof adjoining the roller 11, the upper ends of the rods being curved away from the plate, as shown. A

gage-bar 27 is mounted slidably on the guide-rods 26, and may be secured at adjusted positions upon the gage-table by means of bolts 28 and thumb-nuts 29, the bolts extending through the slots in the table so that the heads thereof are beneath the same.

At each corner of the front side of the machine are secured lugs 30 having vertical openings therein for receiving rods 31 which carry at the upper ends thereof the stock-tables 32. Said tables are adapted to carry the stock or material to be folded, and are arranged at each side of the machine so that the operator may use either or, preferably, both hands for feeding the material to the folding mechanism. The rods 31 may be either rotated or moved vertically through the lugs 30 in order to place the tables at convenient positions, the rods being held in adjusted position by means of set-screws 33, as shown in Fig. 1. In feeding paper to the machine, a sheet is placed on the table 22 and pushed down across the folding-rollers 11 and 12, over the gage-table 23 and beneath the guide-rods 26, until the lower edge of the sheet engages the gage-bar 27. The sheet is then creased and pushed down between the rollers by means of the knife or tapper-blade 34.

The blade 34 is carried by arms 35 secured to a transverse shaft 36 which is pivoted in the frame and extends beneath the gage-table 23. An arm 37 extends diagonally downward and rearward from the shaft 36, the lower end of the arm being adjacent to a cam 38 on the cam-shaft 21. A rod 39 is pivotally connected with the arm 37 and extends slidably through a block 40 pivoted on the frame. A collar 41 is secured on said rod, and a spring 42 is disposed around the rod between the collar and the block 40, so that the pressure of the spring tends to press the arm 37 toward the cam. At the side of the arm 37 adjacent to the cam, a flexible plate or tongue 43 is disposed in spaced relation thereto, one end of the tongue being fixedly secured to the arm and the other end bearing against the end of a screw 44 which passes through the end of the arm, as shown. The tongue is held, by pressure of the spring 42, in constant engagement with the cam, and the relation of the tongue and arm may be varied by adjustments of the screw 44 to compensate wear of the parts and to vary the depth to which the tapper-blade 34 is permitted to pass down between the folding-rollers 11 and 12.

For preventing the descent of the tapper-blade, to avoid the folding of a sheet when the same has not been fed into proper engagement with the gage-bar, a bent lever 45 is pivoted on one side of the frame. Said lever has a long arm which extends downwardly from the fulcrum, and a short arm 35 at the upper part thereof which carries a

pin 46 extending beneath one of the tapper-blade arms 35, as shown in Fig. 3. When the lower arm of the lever is pushed rearwardly said pin 46 is raised to a position at which it will prevent descent of the tapper-blade. For actuating the throw-off lever, the lower arm thereof has connected therewith a rod 47 which extends slidably through the front part of the frame and carries at its front end a semi-circular socket-piece 48 which may be engaged by the leg or knee of the operator to push the rod rearwardly.

As the folded sheets pass out beneath the rollers 11 and 12, they are received by a reciprocating carrier and thereby conveyed into a receiver therefor, of which the construction is as follows:

Near each side of the machine, and extending between the front and rear members of the frame-portion 2 are horizontal guide-rods 49. On said rods there is slidably mounted a U-shaped bar 50 of which the end-portions extend upwardly and are provided with openings through which the guide-rods pass. To the ends of the U-bar 50 are secured the rear ends of side-bars 51 which extend forward horizontally therefrom and rest on the upper side of the front member of the frame-portion 2 between lugs 52 thereon. To the front ends of the bars 51 is secured a cross-bar 53 which carries the vertical end-rods 54. To the cross-bar 53 there are also secured the front ends of a plurality of bottom-rods 55 which extend back at the same level as the side-bars 51 to points above the transverse portion of the U-bar 50, thence curving downwardly and having their ends secured to said portion of the U-bar. The arrangement of the described parts of the slide-frame is clearly shown in Fig. 4.

On the front portions of the guide-rods 49 a transverse cross-bar 56 is slidably mounted. On the rearward side of said cross-bar are a plurality of fingers 57 from which rods 58 extend up parallel with the end-rods 54 of the sliding receiver-frame, the upper ends of said rods 58 being curved slightly rearward. At the center of the cross-bar 56 a flat bar 76 is pivotally connected therewith and extends to a crank-pin 59 carried on the side of an eccentric 60 which is secured on the cam-shaft 21. During rotation of the cam-shaft said crank-pin 59 and connecting-rod 76 serve to impart a reciprocating movement to the cross-bar 56 and the parts carried thereby.

On the rearward side of the machine frame, a transverse shaft 61 is pivotally mounted in suitable bearings, and from said shaft a plurality of arms 62 extend forwardly, said arms being spaced transversely so as to lie in vertical planes not coinciding with the vertical planes of the longitudinal members 51 and 55 of the sliding

receiver-frame, or with the vertical planes of the fingers 57 and rods 58 of the reciprocating frame. On the central part of the shaft 61 is an arm 63 which extends adjacent to the eccentric 60 and carries a roller 64 which bears upon the periphery of the eccentric. Near one end of the shaft 61 is an arm 65 with which a rod 66 is pivotally connected, said rod extending slidably through a block 67 pivoted on the frame. Collars 68 and 69 are secured on said rod 66, and between the respective collars and the block 67 coil springs 70 and 71 are disposed around the rod. The spring 70 serves to hold the roller 64 in engagement with the eccentric so that during rotation of the cam-shaft an oscillating movement will be thereby imparted to the shaft 61 and the arms carried thereby. The spring 71 serves as a buffer to cushion return movement of the parts caused by the other spring.

On each of the arms 62 near the front end thereof a curved rod 72 is secured thereto and extends upwardly therefrom. Each of the arms 62 also carries at its end a bent rod having a U-shaped portion 73 extending downwardly from the arm, and a portion 74 extending up from the front side of the U-portion past the end of the arm to a point slightly below and in front of the upper end of the rod 72.

The extent of the oscillating movement imparted by the eccentric 60 to the shaft 61 is such that at one extreme of the movement the arms 62 are raised to a position at which the upper ends of the rods 72 and 74 are adjacent, respectively, to the rollers 11 and 12, as shown by dotted lines in Fig. 2, while at the other extreme of the movement said ends of the rods are below the level of the longitudinal members 51 and 55 of the sliding receiver-frame, as shown in Fig. 1 and by the full lines in Fig. 2. The various parts of the mechanism are so arranged, and the operation thereof so timed, that the tapper-blade starts a sheet between the folding-rollers slightly before the time that the arms 62 of the oscillating carrier reach their uppermost position, and said arms begin their downward movement at about the same time that the lower edge of the folded sheet engages the arms at the bottom of the spaces between the rods 72 and 74. The arms then move downwardly at substantially the same speed at which the folded sheet is fed out from between the folding-rollers. The movement of the reciprocating cross-bar 56 is so timed that after the arms 62 have reached an intermediate position during their upward movement, and during the completion of said upward movement, but before the folded sheet is fed by the folding rollers into the space between the rods 72 and 74, the rods 58 are moved rearwardly to positions be-

hind the rods 72 of the oscillating carrier. Then during the downward movement of the carrier the folded sheet is carried down in front of the rods 58, being deposited by the carrier on the bottom-rod of the sliding receiver-frame, which serve to strip the sheet from the carrier. The reciprocating packer, formed by the cross-bar 56 and rods 58, moves forwardly during the time that the rods 72 and 74 are below the level of the bottom-rod 55, so that the folded sheet is thereby pushed forward, and as the carrier again moves upwardly the rods 74 pass up behind the folded sheet or sheets in the carrier. Then as the packer-rod 58 are again moved rearwardly the folded sheet is prevented from moving backwardly by engaging the front sides of the rods 74, and of the continuation thereof which forms the front sides of the U-portion 73.

The operation of the described mechanism will be clearly apparent from Fig. 2, wherein a plurality of the folded sheets A are shown in the receiver, a sheet a being shown in position over the folding-rollers 90 ready to be started between them by the tapper-blade, a sheet b being indicated by dotted lines as being started between the rollers, a sheet c being indicated by dotted lines as within the oscillating carrier at the 95 uppermost position thereof, and a sheet d being represented by dotted lines in the position at which it is stripped from the carrier by the bottom-rod of the receiver. The relative positions of the oscillating carrier and of the reciprocating packer devices are shown in Fig. 2 by full and dotted lines, respectively, when the carrier is in the lowermost and in the uppermost positions thereof.

It will be seen that, as the space between the end-rod 54 of the receiver and the rods 58 of the packer becomes filled with the folded sheets, the sliding frame will be successively pushed forward by the pressure 110 of the packer against the folded sheets, so that the capacity of the receiver will be automatically proportioned to the amount of the folded sheets contained therein. It will also be seen that when the folded sheets are removed from the receiver, it is merely necessary for the operator to push the sliding frame rearwardly to its initial position, and that no adjustment of the packing or receiving devices is necessary to enable the same to operate upon sheets of any size within the capacity of the folding mechanism. It will be noted further that the only adjustment of the folding mechanism necessary to enable the folding of any sheet 115 within the capacity of the machine, is the setting of the gage-bar 27 at the desired distance below the tapper-blade and folding-rollers.

Now, having described my invention,

what I claim and desire to secure by Letters Patent is:

1. In a machine of the class described, folding-rollers, an oscillating carrier adapted to receive sheets issuing from the folding-rollers and to carry same away from the rollers, a reciprocating packer movable synchronously with the carrier so as to be at one side of the carrier during movement 10 of the latter away from the rollers and to be at the other side of the carrier during the movement thereof toward the rollers, and relatively fixed members for receiving the sheets from the carrier during the movement thereof away from the rollers.

2. In a machine of the class described, a reciprocating carrier having spaced members adapted to receive a sheet between them, means for delivering sheets into the carrier, a receiver having relatively fixed members intersecting the path of the sheet to strip the same from the carrier, and a reciprocating packer having members interspaced with the carrier-members and adapted 25 to push the sheets in the receiver out of the way of the carrier during the return movement thereof.

3. In a machine of the class described, a horizontally slidable receiver-frame having 30 end-members and transversely-spaced bottom-members, a reciprocating packer hav-

ing vertical members adapted to coöperate with the end members of the receiver-frame to hold sheets between them, and vertically-reciprocating members interspaced with the 35 bottom-members of the receiver-frame, said vertically-reciprocating members being adapted to move in one direction while the vertical packer-members are behind them and to move in the other direction while 40 said packer-members are in front of them.

4. In a machine of the class described, packing and receiving mechanism comprising a horizontally-slidable receiver-frame having vertical end-members and horizontal 45 transversely spaced bottom-members, a horizontally-reciprocating packer having vertical members interspaced with the bottom-members of the receiver-frame, vertically-reciprocating carrier-members transversely 50 interspaced with the bottom-members of the receiver-frame, and actuating means for the packer and carrier-members, whereby the vertical members of the packer are moved toward the end-members of the receiver-frame across the plane of movement of the carrier-members while the latter are below the bottom of the receiver, and are moved to the opposite position while the carrier-members are above the bottom of the receiver. 55

C. A. SIGAFOOS.
